(57) **CLAIM**

The ornamental design for a truck for removing snow and the like, as shown and described.

DESCRIPTION

FIG. 1 is a perspective, front, left side view of an embodiment of a truck for removing snow and the like according to the present invention;

FIG. 2 is a right side view of the truck of FIG. 1;

FIG. 3 is a left side view of the truck of FIG. 1;

FIG. 4 is a front view of the truck of FIG. 1;

FIG. 5 is a rear view of the truck of FIG. 1;

FIG. 6 is a top view of the truck of FIG. 1;

FIG. 7 is a perspective, front, left side view of another embodiment of a truck for removing snow and the like according to the present invention, wherein snowflake surface ornamentations are upon and raised above the outer surfaces of the pipes;

FIG. 8 is a right side view of the truck of FIG. 7;

FIG. 9 is a left side view of the truck of FIG. 7;

FIG. 10 is a front view of the truck of FIG. 7;

FIG. 11 is a rear view of the truck of FIG. 7; and,

FIG. 12 is a top view of the truck of FIG. 7.

The broken lines shown in the drawing views are included for illustrative purposes only and form no part of the claimed design.
